INVENTOR.

BY Louis Barnett

ATTORNEY.

UNITED STATES PATENT OFFICE

106,044

DESIGN FOR A TEA BALL PACKAGE OR SIMILAR ARTICLE

Louis Hirschhorn, New York, N. Y., assignor to Millie Patent Holding Co., Inc., New York,
N. Y., a corporation of New York

Application February 13, 1935, Serial No. 55,385

Term of patent 14 years

To all whom it may concern:

Be it known that Louis Hirschhorn, a citizen of the United States and resident of New York city, in the county of the Bronx and State of New York, has invented a new, original, and ornamental Design for a Tea Ball Package or Similar Article, of which the following is a specification, reference being had to the accompanying drawing, forming part thereof, in which, the figure shows a perspective view of a tea ball package showing my new design.

I claim:

The ornamental design for a tea ball package or similar article, as shown.

LOUIS HIRSCHHORN.
